TWO-WHEELED VEHICLE

Robert J. Proffer, 6090 Sonny Ave.,
Flushing, Mich. 48473

Filed Apr. 25, 1969, Ser. No. 16,898

Term of patent 14 years

Int. Cl. D12—11

U.S. Cl. D90—8

I claim:

The ornamental design for a two-wheeled vehicle, substantially as shown.
